DISPENSING MACHINE

Philip D. Parsons, Swarthmore, Pa., assignor to
 Scott Paper Company, Chester, Pa., a corporation
 of Pennsylvania

Application February 25, 1939, Serial No. 258,475

5 Claims. (Cl. 312—51)

This invention relates to improvements in vending machines, and a principal object of the invention is to provide a coin-actuated machine of this class which shall be relatively simple in mechanical form, and both highly efficient and substantially fool-proof in operation.

Another object of the invention is to provide a novel and generally improved coin-actuated mechanism of the stated class.

Still another object of the invention is to provide a novel and improved vending machine for paper towels and the like.

The invention further resides in the structural and functional features and in the details of mechanism hereinafter set forth and illustrated in the attached drawings, in which:

Figure 1 is a front elevational view of a towel-vending machine made in accordance with my invention;

Fig. 2 is a side elevational view of the machine;

Fig. 3 is a view of the machine with one of the end members removed to show certain details of the actuating mechanism;

Fig. 4 is an inside elevational view of the aforesaid end member showing the coin compartment;

Fig. 5 is a side view of the end member;

Fig. 6 is a sectional view on the line 6—6, Fig. 3;

Fig. 7 is a sectional view on the line 7—7, Fig. 6;

Fig. 8 is a fragmentary front elevational view illustrating a detail of the device;

Figs. 9 and 10 are enlarged fragmentary end elevational views illustrating details of the coin mechanism;

Fig. 11 is a fragmentary view in perspective of one of the elements of the coin mechanism;

Fig. 12 is a section on the line 12—12, Fig. 6, and

Figs. 13, 14 and 15 are fragmentary sectional views on the line 7—7, Fig. 6, illustrating the details and mode of operation of the towel-discharging elements.

With reference to the drawings, the towel-dispensing device therein illustrated comprises a casing 1 having in the interior a compartment 2 for reception of a stack of towels 3, from which stack the towels are adapted to be individually withdrawn, by mechanism hereinafter described, and discharged from the casing through a transverse slot 4. The cabinet is composed in the present instance of a central portion 5 which forms the top, rear and bottom walls, 6, 7 and 55

8 respectively, of the cabinet, two end members 9 and 11 which form the side walls of the cabinet and which are secured in place upon the central portion 5 by means of the tie bolts 12, and the front panel 13 which is hinged at the bottom upon a rod 14 extending between the end members 9 and 11 and which at the top is provided with a suitable lock 15 whereby this panel may be normally retained in the cabinet-closing position. The lower edge of the panel 13 defines the upper edge of the discharge slot 4. The end member 11 forms a housing for the coin mechanism, as hereinafter described, and is provided with a separate detachable panel 16 which is held in place in the end member by lugs 17 at the bottom and at the top by a suitable lock 18.

Rotatably mounted upon a shaft 19 fixed in the end members 9 and 11 at the bottom of the cabinet is a perforated cylinder 21. Secured at 20 one end of the cylinder 21 is a cam 20, and to the outer side of this cam is secured a gear 22 which meshes with a gear 23, this latter gear having secured thereto and projecting through an opening in the end member 11 a knob or handle 24 by 25 means of which the said gear may be rotated to actuate the pinion 22 and to thereby turn the cylinder 21. To the opposite end of the cylinder 21 is secured a ratchet wheel 25 which is housed in the end member 9 and which is connected to 30 the fixed shaft 19 by means of a coiled spring 27. A pawl 28 pivotally secured at 29 to the inside of the end member 9 coacts with the ratchet wheel 25 in a manner hereinafter described.

As shown in Figs. 13, 14 and 15, the cylinder 35 21 occupies a position immediately below the towel stack 3, this stack being supported upon flanges 31 and 32 at the front and rear of the cabinet respectively. The individual towels are folded in flattened C-formation with the infolded 40 opposite longitudinal edge portions of the towel facing downward, and these infolded flaps of the lowermost towel of the stack thereby bear respectively upon the flanges 31 and 32. The flange 31 is inclined inwardly and downwardly 45 towards the cylinder 21, and the flap 33 of the lowermost towel which bears against this flange 31 thus assumes a similarly inclined position, see Figs. 13, 14 and 15, and extends downwardly and inwardly to a point in proximity to the surface of the cylinder 21. The cylinder 21 has projecting therefrom a rigid substantially tangential flange 34, and this flange when the cylinder is 50 rotated is adapted to engage the flap 33 of the lowermost towel, as shown in Fig. 13, and to withdraw the towel from the bottom of the

stack, as shown in Fig. 14. The towel which is designated in Fig. 14 by the reference numeral 35 is carried by the flange 34 to the position shown, at which point the outer edge of the flange engages the under side of a stop element 36 in the interior of the cabinet, thereby preventing further movement in that direction of the cylinder. It will be noted that in this position the forward edge of the towel lies inwardly of the discharge slot 4 and opposite the lower edge of the latter, so that if in this position the cylinder is released, the spring 27, which has been tensioned by the aforescribed rotary movement of the cylinder, will cause the latter to turn backwardly to its original position, thereby projecting the towel from the discharge slot 4, as shown in Fig. 15. In order to prevent the towel from falling freely from the cabinet, the latter is provided at each side of the discharge slot 4 with a projecting pin, 37, 37, which engage behind the flap 33 of the towel, as shown in Fig. 15, to thereby retain the towel in the projected position, from which it may readily be withdrawn for use.

The cylinder 21 is shown in its normal position in Fig. 7. It will be noted that in this position the flange 34 of the cylinder lies in abutment with the inner edge of the inwardly projecting stop flange 36, thereby limiting the rotation of the cylinder in the reverse direction by the spring 27. It will be noted further that in this normal position of the cylinder 21, the pawl 28, which is weighted, hangs freely in a normal position with the working end thereof extending into a recess 38 in the ratchet 25. When the cylinder 21 is rotated in the direction of the arrows in Fig. 13 for discharge of one of the towels from the stack 3 in the manner previously described, the pawl 28 by engagement with the end wall of the recess 38 will be swung to the left, as shown in Fig. 12, and will in this position and by engagement with any one of the ratchet teeth prevent a reverse rotation of the cylinder 21 until the latter has been rotated to the full extent permitted by the stop element 36. In this advanced position of the cylinder, the pawl 28 will enter a second recess 39 in the ratchet 25, and will thereby be permitted to move by gravity into the normal position in which it is shown, for example, in Fig. 7. If now the turning knob 24 is released, the spring 27 will react as previously described to turn the cylinder 21 in the reverse direction toward its normal position, in which it is shown in Fig. 7, and in this reverse movement, the pawl 28 will be swung by engagement with the end of the recess 39 into an angular position which is the reverse of that shown in Fig. 12, and will, therefore, be inoperative to prevent the reverse rotary movement of the cylinder 21 to the normal position. It will be apparent that by means of this device a return of the cylinder to the normal position after the advance movement has once been initiated is prevented until the cylinder has been completely advanced to the maximum extent or until the flange 34 engages the under side of the stop 36.

The coin control mechanism, which as previously set forth is housed in the end member 11 of the casing, is shown in Figs. 3 and 9 to 11, inclusive. It consists of a bell crank lever 41 which is pivotally secured in the end member 11 upon a shaft 42. One arm 43 of this lever extends transversely and normally rests upon the surface of the cam 20, and the other arm 44 of the lever extends upwardly and is formed at the top after

the manner best illustrated in Fig. 11. As therein shown, the upper end of the arm is formed with two relatively spaced projecting flanges 45 and 46, said flanges forming therebetween a slot 5 for reception of a coin, as hereinafter described. The bases of the flanges are connected by means of a web 47, shown in dotted lines in Fig. 11, the upper edge of this web being formed on an arc more or less closely conforming to the circumference of the coin and forming a seat for the latter. The outer end of the flange 45 is provided on its inner face with a triangular lug 48, the function of which will be hereinafter described.

As shown in Figs. 9 and 10, the lever 41 occupies a position such that the upper flanged end of the arm 44, or rather the slot between the flanges 45 and 46 of this arm, occupies a position immediately below and in alignment with the lower end of a coin slot 49 which is formed in the end member 11, the upper end of this slot intersecting the forward edge of said end member, as shown in Figs. 1 and 9. Thus when a coin is inserted in the slot 49, it will pass downwardly and into the space between the flanges 45 and 46 of the arm 44. The normal position of the lever 41 is determined by a leaf spring 51 which is confined between the arm 44 and the adjoining wall of the end member 11, and which exerts pressure tending to turn the lever as a whole in a clockwise direction, as viewed in Fig. 3, this clockwise movement of the lever being limited by the engagement of the outer end of the arm 43 with the surface of the cam 20. In this normal position of the lever, the arm 44 lies in such proximity to a fixed lug 52 in the end member 11 that a coin passing downwardly from the slot 49 and into the space between the flanges 45 and 46 of the arm 44 is prevented from passing between the said flanges, and is retained upon the curved seat of the web 47, as shown in Fig. 9, wherein the coin referred to is designated by the reference numeral 53. It is apparent that for release of this coin the arm 44 must be moved away from the fixed lug 52 against the tension of the spring 51.

It will be noted that the coin 53, which is confined as described above between the curved upper edge of the web 47 at the back of the slot between the flanges 45 and 46 and the fixed lug 52, functions to prevent any movement of the arm 44 in the direction of the lug 52. If, therefore, the cam 20 is rotated in the direction of the arrow in Fig. 3, which rotation occurs when the knob 24 is turned in the clockwise direction, as viewed in the same figure, for discharge of a towel as described above, the arm 43 of the lever 41 will be held fixed in the position shown, and will not follow the recessed contour of the cam. It will be noted that in the normal position of the cam 20 and the lever 41, the outer end of the arm 43 bears upon a portion of the cam which is radially inset from the outer cam surface. It will be noted also that as the cam 20 is rotated from the normal position in the direction of the arrow, as shown in Fig. 3, the contacting end of the arm 43 will eventually ride up on the outer periphery of the cam at the point indicated by the reference numeral 54, and that when this engagement occurs, the arm 43 will be slightly elevated from its normal position, and the arm 44 of the lever will thereby be moved outwardly against the pressure of the spring 51 sufficiently far to free the coin 53 from the retarding lug 52, the coin thus freed dropping

downwardly by gravity from between the flanges 45 and 46 and being deposited in a coin-receiving pocket 55 formed on the inside of the member 16.

With further reference to Fig. 3, it will be noted that between the point 56 where the arm 43 of the lever 41 normally engages the cam 20 and the point 54, the cam is provided with teeth 57 which would act normally to preclude the rotation of the cam 20. When, however, a coin occupies the space between the flanges 45 and 46 of the arm 44 of the lever and lies in engagement with the fixed lug 52, the lever 41 is prevented from moving to the right, as viewed in Fig. 3, so that the arm 43 is retained in the position shown, all as previously set forth. The tips of the teeth 57 are slightly inset radially from the point 56 at which the arm 43 normally engages the cam so that the arm 43 is prevented by the coin 53 from engaging the teeth 57. In the absence of the coin 53, it will be apparent that the spring 51 would cause the arm 43 of the bell crank lever to engage the near tooth 57, and would thereby prevent the cam from being rotated except through a relatively small angle.

It will be apparent from the foregoing description that the deposit of a single coin in the slot 49 will permit an operator to free one towel from the cabinet, and in order to facilitate the operation of the vending machine if more than one towel is required, the slot 49 is made of sufficient depth to permit of simultaneous insertion of at least three coins, as shown in Figs. 9 and 10. When as previously described the lever 44 is moved in the counterclockwise direction, as viewed for example in Fig. 10, to release the coin 53, the lug 48 on the flange 45 will have moved to the position shown in Fig. 10, in which position it blocks the coin slot channel and prevents the succeeding coin, designated 58 in the drawings, from passing downwardly in the slot. The coin 58, therefore, remains in its original position until the arm 44 of the lever is moved forwardly into the normal position, at which time this coin drops downwardly between the flanges 45 and 46 and is retained between the flanges by the lug 52. It is now possible for the operator to again rotate the cam 20 in the direction of the arrow in Fig. 3 until the point 54 is reached, when the lever 41 will again be rocked against the pressure of the spring 51 to permit the coin 58 to pass into the coin chamber 55. The same sequence of operations then follows with respect to the third coin 59.

In the operation of the machine it will be apparent that discharge of the lowermost towel of the stack is normally prevented by action of the arm 43 of the bell chank lever 41 and the teeth 57 of the cam 20, as previously set forth. Upon insertion of a coin, however, it is possible to turn the cylinder 21 through the medium of the knob 24 in the direction of the arrows in Fig. 13 to an extent releasing one of the towels from the stack, and this towel will be discharged from the slot 4 when the knob 24 is released to permit the spring 27 to return the cylinder 21 to its original position. The ratchet 25 and the pawl 28 afford assurance that a towel will be delivered for each coin inserted in the machine, and preclude loss of a coin due, for example, to premature release of the knob 24 by the operator. Thus the pawl 28 prevents the recessional movement of the cylinder 21 by action of the spring 27 until the cylinder has been advanced in the towel-discharging operation to the full extent of its movement

and until the flange 34 contacts the stop flange 36. The ratchet 25 and pawl 28 function not only to insure a proper delivery of the individual towels after insertion of the coin, but also insure that the towels will be withdrawn from the stack and delivered through the slot 4 in normal sequence, and thereby preclude jamming of the machine by reason of non-delivery of any one towel after withdrawal or partial withdrawal of the towel from the stack.

As shown in Fig. 8, the front panel 13 of the cabinet is provided with a window 61 through which the towel stack 3 is visible, so that the device may more readily be serviced and a constant supply of towels maintained. In the event, however, that the towels become completely exhausted, provision is made for indicating this condition from the front of the cabinet to thereby preclude the useless insertion and loss of coins in the machine. With reference to Figs. 7 and 8, it will be noted that immediately above the window 61 a flap 62 is hinged to the inner face of the panel 13. Normally this flap 62 is retained in an elevated position, as shown in Fig. 7, by the towel stack. When, however, the stack falls below the hinge 63 of the flap, the latter is permitted to move inwardly upon its hinge by gravity, until when the towels are completely exhausted, this flap will occupy a position obstructing the window 61. As shown in Fig. 8, the flap 62 is marked with the word "Empty," and when the flap is in the window-obstructing position, see Fig. 1, the word is visible through the window, thereby warning that the supply of towels in the cabinet has been exhausted.

It will be noted that the inner wall of the coin pocket 55 is provided with perforations 64 which are not sufficiently large to permit the passage of the coins but through which the coins are visible in the interior of the pocket. It will be noted further that the inner wall of the end member 11 opposite the coin pocket 55 is provided with a series of apertures 65, see Figures 3 and 6, so that through these apertures and the aforesaid perforations 64 visibility may be had from the interior of the cabinet proper to the interior of the coin pocket 55. By this means, it is possible for the individual or individuals servicing the device to determine the level of the coins in the coin pocket without the necessity for removing the panel 16, and this panel, therefore, need be removed only at such time as the number of coins approaches the capacity of the coin pocket.

55 I claim:

1. In an article-dispensing machine, a casing having a delivery port, a support in the casing for said articles, a rotary member positioned in an intermediate position between said port and the support, means for limiting the rotary movement of said member in both directions, article-engaging means on the member arranged first to engage and then to withdraw an article from the support to a position opposite the delivery port when the said member is rotated continuously between said limits in one direction, and to discharge the said article through the delivery port when the member is subsequently moved in the reverse direction, and means for actuating said member.

2. In an article-dispensing machine, a casing having a delivery port, a support in said casing for said articles, a member mounted in the casing for successive movements in opposite directions, means for limiting the movement of the member

in both directions, article-engaging means on the member arranged to withdraw an article from the support to a position opposite the delivery port when the said member is moved continuously between said limits in one direction, and to discharge the said article through the delivery port when the member is subsequently moved in the reverse direction, and means precluding initiation of said reverse movement until the member has reached the limit of its movement in the first direction, said means comprising a ratchet connected to and movable with said member, a pawl coacting with said ratchet, means for normally retaining said pawl in a normal neutral position in which it is inoperative to prevent movement of said ratchet in either direction, means automatically operative at the beginning of the first of said movements to adjust said pawl into a position operative to prevent the reverse movement of the ratchet, and means automatically operative at the beginning of said reverse movement to adjust said pawl into a secondary position in which it is inoperative to prevent said reverse movement.

3. In an article-dispensing machine, a casing having a delivery port, a support in said casing for said articles, a rotary member positioned in an intermediate position between said port and the support, said member being adapted when rotated in one direction to engage and withdraw an article from said support and to carry said article to a position opposite said port, and when subsequently rotated in the opposite direction to propel said article through the port, manual means for rotating the said member in one direction, and resilient means for rotating the said member in the opposite direction.

4. In an article-dispensing machine, a casing

having a delivery port, a support in said casing for said articles, a rotary member positioned in an intermediate position between said port and the support, said member being adapted when rotated in one direction to engage and withdraw an article from said support and to carry said article to a position opposite said port, and when subsequently rotated in the opposite direction to propel said article through the port, manual means for rotating the said member in one direction, resilient means for rotating the said member in the opposite direction, and means for limiting the rotary movement of said member in both directions.

5. In a dispensing machine, a casing having a delivery port, a support in the casing for a stack of folded paper towels, said support comprising a shoulder at each of two opposite sides of the casing constituting seats for opposite sides of the stack, one of said shoulders being formed so as to permit a folded edge of the lowermost towel to depend from the normal plane of the bottom of the stack, a rotary member positioned in an intermediate position between said port and the support and having thereon a projecting flange adapted when the member is rotated in one direction to engage the said folded edge of the lowermost towel, the shoulder supporting said edge being relatively narrow and permitting the flange by continued rotation in the said one direction to withdraw the towel from the support to a position wherein the opposite edge of the towel lies in alignment with the said delivery port, whereby when the member is rotated in the reverse direction the said flange is operative to sweep the towel through said port.

PHILIP D. PARSONS.
